UNITED STATES PATENT OFFICE.

CHARLES J. VERNON AND WALTER A. CHOATE, OF LOS ANGELES, CALIFORNIA; SAID CHOATE ASSIGNOR TO SAID VERNON; CORA B. VERNON ADMINISTRATRIX OF SAID CHARLES J. VERNON, DECEASED.

FRUIT-PEELING APPARATUS.

SPECIFICATION forming part of Letters Patent No. 739,953, dated September 29, 1903.

Application filed January 17, 1902. Serial No. 90,215. (No model.)

To all whom it may concern:

Be it known that we, CHARLES J. VERNON and WALTER A. CHOATE, citizens of the United States, residing at Los Angeles, in the 5 county of Los Angeles and State of California, have invented a new and useful Fruit-Peeling Apparatus, of which the following is a specification.

This invention relates to apparatus for 10 handling fruit, and particularly to means for conveying and treating fruit; and some of the objects of the invention are to provide means of this character which will be simple and cheap in construction and effective for the 15 purpose intended.

Another object of the invention is to provide a device constructed to retain liquid and to transport the fruit and discharge the same into the liquid when desired.

20 With these and other objects in view the invention consists, essentially, in the construction, combination, and arrangement of parts, substantially as more fully described in the following specification and as illustrated in the accompanying drawings, forming 25 part of this application, in which—

Figure 1 is a top plan view of the conveyer-table, showing two of the gates open. Fig. 2 is a side elevational view of the same. Fig. 3 30 is a part sectional side elevational view partly broken away, and Fig. 4 is a cross-sectional view of the conveyer-table.

Similar characters of reference designate 35 corresponding parts throughout the several views.

Referring to the drawings, the reference character 1 designates the legs or supports of the conveyer-table, secured to the parallel side pieces 2, to the upper edge whereof are 40 secured laterally-extending plates or ledges 3, having braces 4 connected therewith and with the legs or supports 1 to afford rigidity to these parts.

Parallel partition or division plates 5 are 45 arranged between and at a distance from the side pieces 2 and are connected therewith by inclined bottom members 6, whereby an intermediate longitudinal space is provided,

on each side whereof are formed liquid chambers or receptacles, as illustrated in Figs. 1 50 and 4 of the drawings.

Between the parallel plates 5 are revolvably mounted pulleys or rollers 9, and the shaft of one of these rollers is preferably extended, as at 10, Fig. 4, and is provided with 55 a band-wheel 11 to receive a driving belt or band by which said roller is actuated in the usual manner. Mounted to travel over said pulleys or rollers 9 is an endless conveyer 12, adapted to receive the fruit or other material 60 to be handled or treated from the inclined chute 13, arranged to deliver the fruit to the endless conveyer, as will be readily understood by those skilled in the art to which this invention appertains. 65

Movably mounted in recesses in the free edge of each of the parallel division-plates 5 or in any other preferred manner are gates 14, preferably arranged in staggered order and constructed to swing across the conveyer 12, 70 as shown at 15 in Fig. 1, and close the space between the division-plates 5 and deflect the fruit or material being transported upon said conveyer into one or other of the liquid-chambers 7 on each side of the endless conveyer 75 12, as will be readily understood.

A trough 16 is preferably mounted beneath the endless conveyer 12 upon cross-pieces 17 to receive the liquid escaping from the liquid-receptacles or from said conveyer or otherwise. 80

The operation of this invention will be readily understood from the foregoing description, when taken in connection with the accompanying drawings and the following explanation thereof. The fruit or material is deposited in the inclined chute 13, which directs it upon the traveling endless conveyer 12, whereby the fruit or material is transported along between the liquid-receptacles 7 90 until the passage thereof is obstructed by one of the gates 14 being swung across between said receptacles, as at 15, Fig. 1, whereupon the traveling fruit is deflected by such gate into one or other of the liquid-receptacles, as 95 the case may be. When the desired amount

- of fruit or material shall have been deposited in one liquid-receptacle, the gate on that side can be closed and a gate on the other side may be opened, whereupon the fruit or material 5 will thereby be discharged into the other receptacle, and by opening different gates the fruit or material can be discharged into different parts of the receptacles or at different places therein.
- 10 It is not desired to confine or limit this invention to the specific construction, combination, and arrangement of parts herein shown and described, and the right is reserved to make all such changes in and modifications of 15 the same as come within the spirit and scope of this invention.

We claim—

1. An apparatus constructed with an intermediate passage for the material, a conveyer 20 in said passage, liquid-receptacles on each side of said passage and means for discharging the material into said liquid-receptacles.
2. An apparatus having an intermediate

passage for the material treated, a conveyer in said passage, liquid-receptacles on each 25 side of said passage and gates pivoted in the walls of said passage and constructed to swing across the same to effect the discharge of the material into said receptacles.

3. An apparatus provided with a tank for 30 liquid, a conveyer for material traversing the same, said tank having retaining-walls at each side arranged to leave the liquid accessible at either side thereof and pivoted gates forming part of said walls and adapted to swing across said conveyer to effect the lateral discharge into the liquid of the material on said conveyer.

In testimony whereof we have signed our names to this specification in the presence of 40 two subscribing witnesses.

CHARLES J. VERNON.
WALTER A. CHIATE.
